UNITED STATES PATENT OFFICE.

GEORGE W. HATCH, OF BROOKLYN, NEW YORK.

IMPROVEMENT IN UMBRELLA-RUNNERS.

Specification forming part of Letters Patent No. 171,802, dated January 4, 1876; application filed July 9, 1875.

To all whom it may concern:

Be it known that I, GEORGE W. HATCH, of Brooklyn, in the county of Kings and State of New York, have invented a new and useful Improvement in Runners for Umbrellas and Parasols, which improvement is fully set forth in the following specification, reference being had to the accompanying drawing, in which—

Figure 1 represents a side view of my runner applied to an umbrella-stick. Fig. 2 is a bottom-end view.

Similar letters indicate corresponding parts.

My invention relates to that class of runners which are retained in a higher or in a lower position on the umbrella-stick by means of a bayonet-joint composed of slots which are formed in the respective ends of the runner, and of studs which project from the upper and lower parts of the umbrella-stick; and my invention consists in combining, with the slots of the runner, a cross-piece, which is raised to admit of a passage of the studs beneath it, said raised portion extending entirely over the slot, by means of which a protection is afforded to the slots, as hereinafter fully set forth.

In the drawing, the letter A designates an umbrella stick or handle, to the upper and lower portions of which are fastened studs B, in any suitable manner. C designates an umbrella-runner, which is fitted on the stick A, and which carries the ordinary notch-ring D for the attachment of the stretchers of the umbrella. This ring D may be loose in order to permit of rotating the runner independently of it; or the ring may be fast to the runner, as in the present example, the stretchers, in this case, permitting of a rotation of the parts sufficiently to lock or unlock the runner on the stick, as hereinafter stated. The respective ends of the runner C have inwardly-projecting slots E, and these slots are provided with return-bends F, projecting outwardly, so as to form a nose, a, within the slots. Thus, when the runner C is moved up or down on the stick A for the purpose of opening or closing the umbrella, and either of the slots E F is made to interlock with its proper stud B, by passing the open end of the

part E over the stud, and then turning the runner so that the stud enters the bend F, the runner is prevented from returning by the nose a, assisted by the inherent tension of the umbrella-body; and by this arrangement I obtain a simple and practical device for locking and keeping the runner in a locked condition.

To release the runner it is only necessary to push it slightly upward or downward, as the case may be, so as to clear the stud B by the nose a, whereupon the runner may be moved in any direction.

The slot E F of the lower end of the runner is covered by a cross-piece, G, which forms part of a ring that encompasses and is fastened to the runner. This cross-piece G is raised above the slot, as shown in Fig. 2, to a sufficient extent as to admit the stud B beneath it, or as not to interrupt the entrance of the stud to the slot.

The cross-piece may be applied to both ends of the runner C—or, in other words, to both the slots E F—if seen fit, and its object is to strengthen and prevent bending of the ends of the slot, as well as to obviate the danger of being caught—as, for instance, by the sleeve, by such ends, or the nose a—in opening or closing the umbrella.

I do not claim an umbrella-runner having one or more bayonet-openings to operate in connection with a stud upon the umbrella-handle, and provided with a rotating notch-ring, as such is not my invention.

What I claim as new, and desire to secure by Letters Patent, is—

The runner C, having the notch-ring D, and formed with one or more inwardly-projecting slots, E, and provided with the cross-piece G, which forms part of the ring that is fastened to the runner, substantially as shown and described.

In testimony that I claim the foregoing I have hereunto set my hand and seal this 1st day of July, 1875.

GEORGE W. HATCH. [L. S.]
